UNITED STATES PATENT OFFICE.

LOUIS FERRARA, OF BROOKLYN, NEW YORK.

SANDPAPER AND RUBBING MACHINE.

Application filed June 22, 1927. Serial No. 200,582.

This invention relates to a new and useful device in the nature of a sand papering or polishing machine for floors, automobile bodies, cabinets, walls, or other surfaces, where a highly smooth finish is required for proper appearance. The invention has for an object the provision of a novel machine which is easily and readily manipulated by hand.

10 A further object of the invention is to provide a machine of novel construction and arrangement of parts hereinafter more fully described, claimed and illustrated in the accompanying drawing.

15 Fig. 1 is a side elevational view of my improved machine partly in section, so as to more clearly show the construction thereof.

Fig. 2 is a front elevational view thereof, 20 partly in section.

Fig. 3 is a transverse sectional view taken on the line 3—3 of Fig. 2.

Fig. 4 is a similar view to that illustrated in Fig. 3 showing the clamping members 25 in a released or disengaged position.

Fig. 5 is a fragmentary sectional view, illustrating a further development of my improved machine.

Fig. 6 is a sectional view taken on the line 30 6—6 of Fig. 2.

As here embodied my improved sand papering and polishing machine comprises a small electric motor 10, of the ordinary type, secured to the casing 11, to which a projecting handle 12 is attached. Upon the shaft 13 of the electric motor a pinion 14 is fixed, this pinion meshing with a gear 15 loose on the stub shaft 16 which is fixed upon the casing 11. Fixed to the face of the gear 15 eccentrically thereto, is a pin 17 that engages in a longitudinal slot 18 in an oscillating lever 19 that is fulcrumed at substantially its center to the motor shaft 13.

The lever 19 has attached at its bottom a 45 forked member 22 having formed therein apertures adapted to receive the pins 21, which engage in apertures formed in the foot member 22, which is rectangularly shaped, and has formed therein elongated 50 recesses, adapted to be engaged by the projecting extremities 24 of the casing 11, and cover plate 20 attached to the casing.

Mounted in suitable bearing members of the casing 11, are the drums 25 and 26, over which are passed a roll of sand paper, or 55 polishing felt, the said sand paper or felt passing over the foot member 22 from one drum to the other, being secured at its extremities to the drums 25 and 26. The sand paper or felt is extended through elongated 60 openings 27 and 28, formed in the clamping members 29 and 30, respectively. The clamping members 29 and 30 are fixed to the ends of the rods 31 and 32, respectively, 65 slidably mounted in bearing elements 33 of the foot member 22. Tension springs 34 act to normally hold the clamping members in engagement with the sand paper or felt, against the foot member 22, so as to lock the sand paper or felt to the foot member. 70 The inner or adjacent ends of the rods 31 and 32 are provided with transverse members 35, between which is positioned a cam 36, that is fixed on the lower end of a rod 37, that extends upwardly through a suitable 75 longitudinal axial aperture in the lever 19, and is partially rotatable in the said lever. The rod 37 has fixed thereto adjacent to its upper end, a laterally projecting pin 38, that is adapted to engage the cover plate 80 20, when the lever reaches each end of its oscillatory movement, to rock the rod 37, so as to momentarily free the clamping members 29 and 30, from the sand paper or felt to permit of the latter being advanced.

The pin 39 is rotatively mounted in the plate 20, and has attached thereto, at one extremity, outside the plate 20, a knob 40 or handle. The collars 41 and 42 are secured to the pin 39, and are positioned at 85 each side, adjacent to the plate 20, so as to rotatively hold the pin 39 in a fixed relative position thereto. The pin 39 is provided with a threaded portion 43, adapted to engage in a threaded aperture formed in the 90 brake collar 44, slidably mounted on the shaft 13.

The latter described construction is such as will permit the brake collar 44 to frictionally engage the said lever 19, when the 100 knob 40 is rotated or turned so as to materially decrease the speed of oscillation of the foot member 22.

The levers 45 and 46 are pivotally at-

tached, as at 47, by a pin, or the like, to the lever 19. The tension springs 48 are attached to the levers 45 and 46, and to the lever 19 so as to normally hold the free extremities 49 and 50, respectively, in engagement with the ratchet wheels 51 and 52, respectively, secured to the said drums 25 and 26. The pin 53 is threadedly attached to the lever 19 and is extended therefrom, through an elongated aperture 54, formed in the casing 11. The knob 55 is attached to the extended extremity of the pin 53. The pin 53 is provided with projecting elements 56 and 57, adapted to engage the levers 45 and 46, respectively, as may be desired, by rotating or turning the knob 55. The latter described construction is such as will permit either one of the levers 45 and 46, to be disengaged with the ratchet wheels, so as to permit the oscillatory movement of the lever 19, to partially rotate either one of the drums 25 or 26, so as to advance the sand paper or felt in the desired direction, and so to reverse the direction of advancement of the said sand paper or felt.

The method of operation and manipulation of my improved machine is obvious from the foregoing description, it being apparent that the rotation of the electric motor will cause the foot member 22 to oscillate and the sand paper or felt to be gradually fed forward. The operator of my improved machine holds the sand paper or felt in engagement with the surface to be treated.

In Fig. 5 of the accompanying drawing, I have shown the extended members 58 provided with dove-tailed elements 59, adapted to slidably engage in similarly shaped openings formed in the extremities of the above mentioned foot member 22. The extended member 58 has a tapered enlarged lower portion 60 so as to permit the sand paper 61 or felt, which is extended over the extended member 59 to be used in corners or crevices. It should be understood that the clamping members 29 and 30 are suitably formed or shaped, so as to accommodate the extended members 58.

The cylindrical members 62 and 63 are slidably mounted in suitable openings formed in the extremities of the extended elements 64 and 65 of the casing 11. The threaded members 66 and 67 are threadedly secured to the wall 68 of the extended elements 64 and 65. The expansion springs 69 are secured to the threaded members 66 and 67, and to the concave members 70 attached to the cylindrical members 62 and 63, so as to normally hold the contact points 71 and 72 in a disengaged position. The contact points 71 are attached to the arm 73, extended from the stud 74 secured to the cylindrical members 62 and 63. The contact points 72 are attached to the extend-

ed members 75 secured to the rods 76, attached to the extended elements 64 and 65 of the said casing 11. A suitable electric wire 77 connects the said extended members 75, similar electric wires 78 being connected to the first mentioned extended members 73 and to the electric motor 10. The above described construction is such as will permit the electric motor 10, to operate my improved device, when the said device is properly or uniformly engaged with the work to be sand papered or polished.

Having thus described my invention, what I claim as new and desire to protect by Letters Patent of the United States is as follows:

1. A sandpaper and rubbing machine comprising a casing, a pair of drums with ratchet wheels mounted therein, a lever oscillatably mounted within the casing and between the drums, means for oscillating said lever, a strip of sandpaper engaged on and between the drums and guided beneath a foot attached to the bottom of the lever, means for locking the strip of sandpaper in position on the foot and periodically releasing the sandpaper allowing advancing, a pair of levers pivotally attached at one of their ends to the first mentioned lever, tension springs attached to the first mentioned lever and to the pair of levers urging the free ends of the pair of levers into engagement with the said ratchet wheels, a pin attached to the first mentioned lever and extending from the casing through an elongated aperture, a knob attached to the free extremity of the pin and elements projecting from the pin engageable with one or the other of the said pair of levers as may be desired by rotating the knob so that one of said pair of levers is disengaged from its normally engaged ratchet wheel so as to permit the oscillatory movement of the first mentioned lever to partially rotate one of the drums during each oscillation.

2. A sandpaper and rubbing machine comprising a casing, a pair of drums with ratchet wheels mounted therein, a lever oscillatably mounted within the casing and between the drums, means for oscillating said lever, a strip of sandpaper engaged on and between the drums and guided beneath a foot attached to the bottom of the lever, means for locking the strip of sandpaper in position on the foot and periodically releasing the sandpaper allowing advancing, a pair of levers pivotally attached at one of their ends to the first mentioned lever, tension springs attached to the first mentioned lever and to the pair of levers urging the free ends of the pair of levers into engagement with the said ratchet wheels, a pin attached to the first mentioned lever and extending from the casing through an elongated aperture, a handle projecting

from the casing and forming a covering for the pin, a knob attached to the free extremity of the pin, and elements projecting from the pin engageable with one or the other of the said pair of levers as may be desired by rotating the knob so that one of said pair of levers is disengaged from its normally engaged ratchet wheel so as to permit the oscillatory movement of the first mentioned lever to partially rotate one of the 10 drums during each oscillation.

In testimony whereof I have affixed my signature.

LOUIS FERRARA.
